UNITED STATES PATENT OFFICE.

ARTIE OPHELIA HURLBUT, OF JACKSONVILLE, FLORIDA.

DESIGN FOR A HANGING BASKET.

Application filed October 24, 1925. Serial No. 15,247. Term of patent 14 years.

To all whom it may concern:

Be it known that I, ARTIE OPHELIA HURLBUT, a citizen of the United States, residing at Jacksonville, in the county of Duval and State of Florida, have invented a new, original, and ornamental Design for a Hanging Basket, of which the following is a specification, and which is illustrated in the accompanying drawing, forming a part thereof.

The figure is a view in elevation of a hanging basket, showing the new design.

I claim:

The ornamental design for a hanging basket, as shown.

ARTIE OPHELIA HURLBUT.
